UNITED STATES PATENT OFFICE.

CARL WM. J. HEDBERG, OF NEW BRITAIN, CONNECTICUT, ASSIGNOR TO RESEARCH CORPORATION, OF NEW YORK, N. Y., A CORPORATION OF NEW YORK.

APPARATUS FOR THE ELECTRICAL TREATMENT OF GASES.

1,319,706.

Specification of Letters Patent.

Patented Oct. 28, 1919.

Application filed February 26, 1918. Serial No. 219,305.

To all whom it may concern:

Be it known that I, CARL WILLIAM JULIUS HEDBERG, a citizen of the United States, residing at New Britain, in the county of 5 Hartford and State of Connecticut, have invented certain new and useful Improvements in Apparatus for the Electrical Treatment of Gases, of which the following is a specification.

10 The present invention relates to apparatus for removing suspended particles from gases or gaseous mixtures by the application of high potential electric charges.

In apparatus of this character comprising 15 principally discharge and collecting electrodes a field of intense electric stress is produced through which the gases are passed. The suspended particles are charged by the discharge electrode and migrate under 20 the influence of this charge toward the collecting electrode.

It is customary to make the discharge electrode of a wire or other longitudinally extending conducting element and the collecting electrode in the form of a plate, box 25 or cylindrical tube. The discharge electrode presents a small surface with the result that the electric field is highly concentrated and forms a zone of stress of great intensity, 30 while near the collecting electrode, on the other hand, since it presents a relatively large area, the intensity of the field is small. The theory on which the arrangement is based is that the particles suspended in the 35 gases should be intensely charged near the discharge electrode to force them transversely of the gas stream toward the collecting electrode and that the collecting electrode in turn should not be able to neutralize 40 this charge or even reverse it. It is the idea to make the migration substantially unidirectional and thereby prevent particles once forced out of the active zone from being returned to it.

45 Some particles drop, due to their own gravity, down through the inactive zone near the collecting electrode into a collecting chamber. Others agglomerate and in that condition fall through the inactive zone into 50 the collecting chamber. Still others are carried along due to the velocity of the gas. The greater portion, however, of the particles are forced against the collecting electrode and collect thereon or adhere thereto 55 forming a gradually increasing deposit.

Such deposit is detrimental to the operation of the apparatus and must be periodically removed.

It is the general object of the present invention to remove suspended particles from 60 gases and a more particular object to keep the collecting electrodes clean while the particles are removed.

Another object is the removal of dust, fumes and other suspended particles from 65 swiftly moving gases.

The apparatus embodying the invention, in order to carry out the objects mentioned, deviates in principle from the usual types above referred to in that the collecting electrode does not present a large surface, co-extensive with the discharge electrode, but has the form of transverse webs presenting 70 circular edges toward the discharge electrode and concentric therewith.

75 The purpose and specific advantages of this construction will appear more clearly in connection with the accompanying drawings, in which—

Figure 1 is an elevation partly in section, 80 and

Fig. 2 a transverse section on line 2—2 of Fig. 1.

In the drawings, 1 represents a box-like structure forming the treater chamber. The 85 gases enter this chamber through the conduit 2, flow upwardly in the chamber and pass off into the atmosphere or may be conducted to some particular place for use or further treatment. In the chamber 1 there are a 90 plurality of transverse webs 3 arranged in tiers from bottom to top. These transverse webs 3 have a relatively large number of perforations 4 equal in size and equally spaced, and the perforations of the different 95 tiers are all in vertical alinement. The webs are of electrical conducting material and constitute in their entirety a collecting electrode.

Through the vertically alined openings 4 100 extend longitudinally extending conductors such as fine wires 5 which form the discharge electrodes. These wires are supported by a frame 6 resting on insulators 7 on the top of the chamber 1 in the customary manner. 105 The frame 6, which electrically interconnects all the wires, is connected to the high tension supply circuit as by a conductor 9. The lower ends of the wires may extend through uniformly spaced openings in a 110

spacing frame 10 and weights 11 may be attached thereto to hold the wires taut. The frame 10 is preferably held in adjusted position relatively to the collecting electrode by 5 means of strain insulators 12.

The apparatus thus far described constitutes a multi-flue treater. The vertically aligned openings 4 define a plurality of flues through which the gases must pass. Between the wires 5 and the circular edges in the transverse webs defining the openings 4 is set up an intense electric field. As the gases pass through the strong electric fields between the central or discharge electrode 15 and the webs or collecting electrodes, charges are induced upon the suspended particles or they receive charges from the ionized gases. These charges move under the influence of the electric fields and take with them the suspended particles to which they are attached. The fields are strongest and the movement of particles is greatest between the discharge electrode and the orifice edges, but the particles do not come to rest in the intense parts of the fields, seeking rather the weak fields adjacent those portions of the webs which are at a distance from the orifices.

This characteristic may be explained in part by calling attention to the phenomenon commonly called "electric wind." The molecules of the gases which have become ionized, and are called ions, and the suspended particles to which electric charges are attached, are propelled rapidly through the gases by the force of the electric field. The movement of these particles and molecules has an aspirating effect upon adjacent gas molecules setting them in motion,—the direction being from the strongest to the weakest part of the field. It is conceded that there are charges of both positive and negative sign present in the gases and they tend to move in opposite directions, but those which tend to move counter-current to the electric wind have to overcome considerable resistance and are probably swept back or neutralized, especially if these charges are endeavoring to take with them suspended particles. By making the central electrode of negative polarity the movement of gases is set up by electrons and negative ions which have a higher velocity than positive ions and the results described above are then the most pronounced and most satisfactory. In fact it is found that practically no particles get to the central electrode and settle upon it. In some instances it has been advantageous to have the orifice edges comparatively sharp and the corresponding field strength adjacent thereto correspondingly great which tends to give a slight back-ionization and a resistance to the depositing of particles, but it is probably the momentum of the particles,

the electric wind, and the gas stream itself which tend to carry the particles past the edges, after which they deposit on those portions of the webs where the electric fields are weak and which are away from the gas stream.

I have found, on the other hand, that with an orifice electrode of the character described the potential difference between the electrodes may be very considerably increased before disruptive discharge takes place as compared with the devices of the prior art mentioned. In other words the potential drop per unit of dielectric distance is considerably increased and thereby the electric stress or ionizing capacity.

The direct result is a general increase of the efficiency of the treater. This form of device is particularly adapted for the treatment of swiftly moving gases.

A distinct advantage gained is that by this arrangement the particles once precipitated are definitely removed from the gas stream. The zones intermediate the orifices 4 are outside the gas current and there is no force tending to bring them back into it.

It is further apparent from this arrangement that the current of dust laden gas as it passes through the apparatus is subjected to repeated changes in direction and velocity of gas flow. The velocity of the gas current is increased as it passes through the orifices and then is diminished as it expands into the space between the collecting electrode plates. This change of direction and diminution of velocity not only permits particles to mechanically settle out of the gas, but is additionally important in that the velocity of the gas current in contact with already deposited material is slow, thereby decreasing the tendency to bring deposited material into suspension in the gas; and particles once driven or carried out of the main rapid current of gas are not again subjected to the influence of the main gas-current flow.

To facilitate the removal of the deposited particles from the treater, the transverse webs 3 are divided into a plurality of pivotally mounted sections 16. The line of division between the separate sections lies substantially in the planes passing through the rows of discharge electrodes and the pivotal movement takes place in planes centrally between the discharge electrodes. Rods 17, to which the sections 16 may be connected in any suitable manner, extend through the chamber 1 and have bearing in opposite walls thereof. At one side these rods 17 extend beyond the outer surface of the wall so that suitable means may be provided for turning them. In the particular instance crank levers 18 are secured to the rods. At their outer ends these crank levers 18 are provided with slots 19. The crank levers 18 of each tier are interconnected by rods 130

or bars 20 having laterally projecting pins 21. These pins 21 extend into the slots 19 and are so spaced along rods 20 that all crank levers 18 have the same angular position. When the rods 20 are reciprocated, the cranks are simultaneously turned through an angle indicated by the relative positions of the cranks in the two bottom rows in Fig. 1. By thus turning the cranks 10 the sections 16 are turned from the position shown in the bottom row to that shown in the second row in Fig. 1, so that the deposit may drop down into a collecting chamber or hopper (not shown) where it may be removed. 15 To facilitate the separation of the deposit from the sections 16, provisions are made for jarring or knocking them during their turning movement. As a convenient means I have shown bars or rods 22 mounted parallel to the pivotal rods 17 and positioned in the path of rotary movement of the sections 16, as indicated in Fig. 1, second row. The rods 20 may be mounted in bearings 23 attached on the outside of the chamber 1. To 20 operate all rods 20 simultaneously, they are interconnected by an arm 24 and toggle joints comprising levers 25 and, bell cranks 26 pivotally interconnected in a manner well understood. The arm 24 terminates in a 25 slotted cross arm 27 engaged by the crank pin 28 on a crank disk 29 which may be driven by a motor 30 all as is well understood. The arm 24 is supported for sliding movement in bearings 31 attached to the 30 wall of the chamber 1.

As indicated, the sections 16 preferably contact along oblique planes for the purpose of alinement and mutual support.

The operation is apparent from the preceding description. When it is desired to rap the collecting electrodes, it is only necessary to start the motor 30 without first disconnecting the apparatus from the line.

In the foregoing an attempt has been made to merely outline the broad principles governing the invention. It is, of course, not necessary to move the orifice plates into alinement each time they are jarred. The translating mechanism may be suitably modified so that the orifice plates repeatedly strike the member 22 without each time returning to the alining position.

In practice the orifice plates may be placed closer together than shown in the drawing as is obvious. In fact, while I have shown all orifice plates as simultaneously operated for tilting movement, I contemplate the separate tilting of the different tiers commencing with the top tier and successively going down to the bottom tier.

I may also restrict the pivotal movement of the orifice plates to a relatively small angle, where the deposit is such that it may be easily removed from the plates.

65 While I have suggested a tilting of the

orifice plates for removing the deposit thereon, such tilting movement is not absolutely essential and provisions may be made for removing the deposit in other ways and by different means than by rotation.

I contemplate these and such other changes as may readily suggest themselves during the application of my invention to different conditions.

What is shown and described is merely for the purpose of illustration.

I claim:

1. In apparatus for the electric treatment of gases, a treater chamber, a collecting electrode consisting of a plurality of spaced 80 electrically interconnected plates in said chamber, a plurality of orifices in each plate, each orifice in each plate being substantially in alinement with an orifice in each of the other plates and a discharge electrode extending through each space defined by alined orifices.

2. In apparatus for the electric treatment of gases, a treater chamber, a plurality of spaced plates in parallel arrangement constituting collecting electrodes, alined orifices in said plates to form a conduit for the gases, a discharge electrode extending through said conduit and means for rapping the plates.

3. In apparatus for the electric treatment of gases, a collecting electrode comprising a treater chamber and a plurality of vertically spaced electrically interconnected plates therein in parallel arrangement, alined orifices in said plates to form a conduit for the gases, a discharge electrode extending through the said conduit and means for removing deposit from the said plates.

4. In apparatus for the electric treatment 105 of gases, a collecting electrode comprising a treater chamber and a plurality of vertically spaced plates therein in parallel arrangement, alined orifices in said plates to form a conduit for the gases, a discharge 110 electrode extending through the said conduit and means acting on the said plates to remove deposit therefrom while the electrodes are charged.

5. In apparatus for the electric treatment 115 of gases, a collecting electrode comprising a treater chamber and a plurality of vertically spaced plates therein in parallel arrangement, alined orifices in said plates to form a conduit for the gases, a discharge electrode 120 extending into the said conduit and means for tilting at will the said plates.

6. In apparatus for the electric treatment of gases, a collecting electrode comprising a treater chamber and a plurality of vertically spaced plates therein in parallel arrangement, alined orifices in said plates to form a conduit for the gases, a discharge electrode extending into the said conduit, means for tilting at will the said plates and 130

means for rapping said plates during the tilting movement.

7. In apparatus for the electric treatment of gases, a collecting electrode comprising a treater chamber and a plurality of vertically spaced plates pivotally mounted therein, alined orifices in said plates to form a conduit for the gases, a discharge electrode extending into the said conduit, means for turning the plates about their pivots and means for rapping them during such turning movement.

8. In apparatus for the electric treatment of gases, a collecting electrode comprising a treater chamber and a plurality of electrically interconnected vertically spaced plates therein, a plurality of orifices in each plate, each orifice in each plate being substantially in alinement with an orifice in each of the other plates, a discharge electrode extending into each space defined by alined orifices and means for removing deposit from the said plates.

9. In apparatus for the electric treatment of gases, a collecting electrode comprising a treater chamber and a plurality of vertically spaced plates therein, a plurality of orifices in each plate, each orifice in each plate being substantially in alinement with an orifice in each of the other plates, a discharge electrode extending into each space defined by alined orifices and means acting on the said plates to remove deposit therefrom while the electrodes are charged.

10. In apparatus for the electric treatment of gases, a collecting electrode comprising a treater chamber and a partition transversely thereof, said partition being composed of a plurality of pivotally mounted sections constructed and arranged to define a plurality of orifices, a discharge elec-

trode extending into each orifice and means for turning each section about its pivot.

11. In apparatus for the electric treatment of gases, a collecting electrode comprising a treater chamber and a partition transversely thereof, said partition being composed of a plurality of pivotally mounted sections constructed and arranged to define a plurality of orifices, a discharge electrode extending into each orifice, means for turning each section about its pivot and means for rapping it during such turning movement.

12. In apparatus for the electric treatment of gases, a collecting electrode comprising a treater chamber and a partition transversely thereof, said partition being composed of a plurality of pivotally mounted sections constructed and arranged to define a plurality of orifices, a discharge electrode extending into each orifice, means for simultaneously turning said sections about their pivots.

13. In apparatus for the electric treatment of gases, a collecting electrode comprising a treater chamber and a partition transversely thereof, said partition being composed of a plurality of pivotally mounted sections constructed and arranged to define a plurality of orifices, a discharge electrode extending into each orifice, means for simultaneously turning said sections about their pivots and means for rapping the sections during such turning movement.

In testimony whereof I affix my signature in presence of two witnesses.

CARL WM. J. HEDBERG.
